UNITED STATES PATENT OFFICE.

GEORGE COUCH, OF ST. LOUIS, MISSOURI.

IMPROVEMENT IN ADJUSTABLE BOOT-JACKS.

Specification forming part of Letters Patent No. 129,936, dated July 30, 1872.

To all whom it may concern:

Be it known that I, GEORGE COUCH, of St. Louis, in the county of St. Louis and State of Missouri, have made a certain new and useful Improved Adjustable Boot-Jack; and I do hereby declare that the following is a full and true description thereof, reference being had to the accompanying drawing and to the letters of reference marked thereon.

The object of this invention is to form an improved boot-jack adapted to the different sizes of boots, &c. The nature thereof consists in providing the boot-jack with a sliding toe attachment, made adjustable to accommodate the wearers' boots, and, by means of its toe-piece, to engage the toe part of the boots in manner now to be more fully described.

To enable those herein skilled to make and use my said improvement, I will now more fully describe the same, referring to—

Figure 1 as a side elevation, to Fig. 2 as a bottom plan.

The boot-jack A is provided with a semi-circular recess, A', for the reception of the boot-heel, in manner usual. The jack A is sup-

ported in inclined position by a bracket-step, a. Through the bracket a, and guided in same, is arranged an adjustable rod, B, carrying at its outer end a toe-piece, C, and at its inner end a collar, b, against which a suitable spring, C', abuts, as shown in Figs. 1 and 2.

The operator inserts the toe of his boot under the curved toe-piece C, and draws it out far enough to enable him to insert the heel of his boot in the heel-recess of the jack; thus he can gage the "pull" on the instep or heel of the boot as desired.

Having thus fully described my said invention, what I claim is—

The arrangement, in an adjustable boot-jack, of the jack A, bracket a, rod B, carrying a coiled spring, C', and toe-piece C, as and for the purpose set forth.

In testimony of said invention I have hereunto set my hand.

GEORGE COUCH.

In presence of—

WILLIAM W. HERTHEL,
ROBERT BURNS.
